[57] CLAIM

The ornamental design for a medical waste station with hypodermic needle cutter, substantially as shown and described.

DESCRIPTION

FIG. 1 is a front perspective view of a medical waste station with hypodermic needle cutter embodying my design;

FIG. 2 is a left side view thereof;

FIG. 3 is a front view thereof;

FIG. 4 is a rear view thereof;

FIG. 5 is a right side view thereof;

FIG. 6 is a top plan view thereof;

FIG. 7 is a bottom plan view thereof;

FIG. 8 is a sectional view taken on line 8—8 of FIG. 1.

Fig. 3
